STEM-WINDING-AND-SETTING TIMEPIECE

Elof L. Carlson, Bristol, Conn., assignor to The E. Ingraham Company, Bristol, Conn., a corporation

Application January 6, 1934, Serial No. 705,533

4 Claims. (Cl. 58—67)

This invention relates to stem-winding-and-setting timepieces, and more particularly to retaining-means for the pivot-screw of the shifter-arm of such timepieces.

5 Heretofore, in stem-winding-and-setting timepieces, the pivot-screw of the shifter-arm has had a marked tendency to become loose notwithstanding repeated efforts over a period of years by those skilled in the art, to overcome this difficulty.

One cause of the previous inability to solve this problem has resided in the fact that timepieces employing this construction have been comparatively small in size and, therefore, place distinct 15 limitations upon the introduction of additional parts for the purpose of solving this problem.

It is, therefore, an object of this invention to provide an improved construction particularly adapted to timepieces of the nature above referred to for effectively preventing the loosening of the first screw of the shifter-arm.

Another object of this invention is to provide such a construction which not only is extremely effective in operation, but which also is of 20 minimum cost, whereby it can be applied to watches of low cost.

With the above and other objects in view, this invention includes the improved features, parts and combinations of parts disclosed in the following description, appended claims and accompanying drawing forming a part of this specification.

In the accompanying drawing, in which one way of carrying out the invention is shown for 35 illustrative purposes:

Fig. 1 is a rear elevation of the movement of a stem-winding-and-setting watch made in accordance with this invention;

Fig. 2 is a left-end elevation of Fig. 1;

40 Fig. 3 is a sectional view on the line 3—3 of Fig. 1;

Fig. 4 is a perspective view of the retaining or locking-plate of this invention; and

Fig. 5 is a fragmentary sectional view on the 45 line 5—5 of Fig. 1.

Referring to the drawing, the watch movement 10 includes front and rear movement-plates 11 and 12 respectively, joined together by means of a plurality of pillars 13 and screws 14.

50 In the usual construction of stem-setting-and-winding watches, the stem 15, having a winding-and-setting button 16, is rotatably engaged with fingers 17 of a shifter-arm 18, which latter is pivotally mounted at 19 on the shifter-arm pivot-screw 20, which pivot-screw has its head 21 ex-

tending out through a hole 22 in the rear movement-plate 12. When the stem 15 is in its innermost position, the shifter-arm 18 is also in its innermost position and, through suitable mechanism, results in the winding of the watch upon the winding-and-setting button 16 being turned in the proper direction.

When the stem 15 is pulled to its outermost position, the engagement of the fingers 17 of the shifter-arm 18 with the stem causes the shifter-arm 18 to be swung about its pivot to its outermost position, to cause the engagement of suitable well-known mechanism with the stem 15, whereby turning of the winding-and-setting button 16 results in the turning of the hands of the 15 watch for the purpose of setting the same, as is well known.

After the watch has been set to its correct position, the stem 15 is again pushed back to its normal innermost position, which carries the 20 shifter-arm to its normal innermost winding position. The construction previously referred to and the mode of winding and setting the watch is all of regular and well-known operation as has been long practiced in the art.

25 The above-described in-and-out shifting of the stem 15 with the shifting back and forth of the shifter-arm 18, all under substantial stress, results in alternating stresses upon the shifter-arm pivot-screw 20, with consequent well-known 30 tendency to loosen the pivot-screw 20 notwithstanding numerous and varied type efforts to overcome this loosening of the pivot-screw.

In accordance with my invention, I provide a retaining or locking-plate 23, preferably of 35 spring steel, having a pocket or cup-portion 24 to fit over the head 21 of the pivot-screw 20 and having an arm 25 provided with an aperture 26 adapted to register with a hole 27 in the rear movement-plate 12 and also register with a 40 threaded hole 28 in one of the pillars 13 (Fig. 3), whereby one of the ordinary standard screws 14 not only engages within the threaded hole 28 in the pillar 13 to do its part in holding the movement-plates 11 and 12 together, but also at the 45 same time serves to hold the retaining-plate 23 in proper position with the pocket 24 over the head 21 of the pivot-screw 20.

If desired, the end of the arm 25 of the retaining-plate beyond the aperture 26 can be provided 50 with a locking-split 29 having a locking-edge 30, or oppositely-extending locking-edges 30 and 31 (Fig. 5), thus further aiding in preventing loosening of the screw 14. This retaining or locking construction which employs my retain- 55

ing-plate 23 is entirely effective in practice in holding the pivot-screw 20 against loosening, and at the same time provides a readily-assembled construction of minimum cost and which is so thin as to not substantially increase the thickness of the time-instrument at this location.

The invention may be carried out in other specific ways than that herein set forth without departing from the spirit and essential characteristics of the invention, and the present embodiment is therefore to be considered in all respects as illustrative and not restrictive, and all changes coming within the meaning and equivalency range of the appended claims are intended to be embraced therein.

I claim:

1. A time-instrument including: a movement-plate provided with a hole therethrough; a shifter-arm pivot-screw having its head extending through said hole; a retaining-plate engaged over the head of said pivot-screw and having an arm; and a removable screw extending through said arm and said movement-plate and serving to removably secure said arm to said movement-plate.

2. A time-instrument including: a movement-plate provided with a hole therethrough; a shifter-arm pivot-screw having its head extending through said hole; a retaining-plate engaged over the head of said pivot-screw and having an arm provided with an aperture near the end of the arm, the end of the arm beyond said aperture being provided with a locking-split; and a screw

extending through said aperture and securing the arm to the movement-plate.

3. A time-instrument including: a pair of movement-plates; means including a pillar connecting said movement-plates together; one of said movement-plates being provided with a first hole and a second hole therethrough; a shifter-arm pivot-screw having its head extending through said first hole; said pillar aligned with said second hole; a retaining-plate engaged over the head of said pivot-screw and having an arm provided with an aperture registering with said second hole; and a screw extending through said aperture and into said pillar and serving both to secure said arm to said one movement-plate and to secure said one movement-plate to said pillar.

4. A time-instrument including: a pair of movement-plates; means including a pillar connecting said movement-plates together; one of said movement-plates being provided with a first hole and a second hole therethrough; a shifter-arm pivot-screw having its head extending through said first hole; said pillar aligned with said second hole; a retaining-plate engaged over the head of said pivot-screw and having an arm provided with an aperture registering with said second hole, the end of said arm beyond said aperture being provided with a locking-split; and a screw extending through said aperture and into said pillar and serving both to secure said arm to said one movement-plate and to secure said one movement-plate to said pillar.

ELOF L. CARLSON.
